UNITED STATES PATENT OFFICE.

JOHN P. KENNY, OF ROCHESTER, NEW YORK.

PNEUMATIC SOLE FOR SHOES AND BOOTS.

1,056,426.

Specification of Letters Patent. Patented Mar. 18, 1913.

Application filed March 13, 1912. Serial No. 683,613.

To all whom it may concern:

Be it known that I, JOHN P. KENNY, a citizen of the United States, residing at the city of Rochester, in the county of Monroe and State of New York, have invented a new and useful Pneumatic Sole for Shoes and Boots, of which the following is a specification.

My invention relates to pneumatic soles used on shoes and boots in walking and running, and the objects of my invention are: (1) to provide an easy, soft and resilient sole for boots and shoes; (2) to provide such a sole, making it attachable to any boot or shoe; (3) to provide said sole with a removable heel; (4) to produce a sole to a boot or shoe that will not slip upon any surface when used by a runner, and which shall be durable, efficient, and neat in appearance. I accomplish these objects by the construction illustrated in the accompanying drawing, in which—

Figure 1 is a side view of a shoe with my pneumatic sole affixed, showing upper and lower layers of the sole; the surrounding wall intervening said layers at their periphery; the air-chamber within, and the heel; Fig. 2 is a longitudinal sectional view, showing the interior thereof, and Fig. 3 is an enlarged vertical sectional view, showing method of attachment of the heel, the position of the air valve and of the retaining plate of the heel.

Similar numerals refer to similar parts throughout the several views.

Referring to the accompanying drawing by numerals, it will be seen that my improved pneumatic sole comprises an inner lining comprising upper and lower walls 1, 40 constructed preferably of canvas, said lining being inclosed by a coating of rubber 2, the outer or lower layer being made the thicker, a side wall 3 preferably of soft but heavy rubber with or without the canvas lining intervening said layers exteriorly and providing an air chamber 4 centrally, said layers being preferably vulcanized to the side wall, a plate 5, provided with prongs 6, 7 and 8, said plate being embedded within

said lower layer of the sole, the prongs 50 thereto protruding through the bottom of the sole, an aperture 9 in said side wall, positioned at the rear and above the heel, a valve 10, through which air is injected in inflating said air chamber, a heel-retaining 55 plate 11, provided with perforated shoulders 12 and 13, which are threaded within and engaged by screws 14 and 15, any desired number of each being used in securing the heel, said heel-retaining plate being embedded within said lower layer of the sole, as shown, and anchorages 16 and 17, through which said screws pass and whereby the heel is securely but removably attached to the sole.

My pneumatic sole for boots or shoes may be constructed by coating the upper and lower body or lining walls 1 with rubber, inserting the side walls 3 between them and then vulcanizing the assembled parts securely together to form a unitary one-piece structure into which the beforementioned plates, if used, and the air valve are incased in the positions described. Of course, the rubber coating on the lower wall should 75 be the thicker because of the wear to which it is necessarily exposed, but the sole as a whole should be sufficiently heavy and, therefore, of sufficient stiffness, to hold its form when cemented or similarly secured with 80 its upper wall against the sole of a shoe, that is, aside from the distortions incident merely to the slight compression and expansion due to the weight of the wearer in walking. This pneumatic sole can be readily 85 attached to any shoe, as is evident, and can be secured to the bottom of the shoe either by stitching or cemented thereto. This sole may, of course, be constructed without the heel or the aforementioned prongs.

What I claim:

As an article of manufacture, a pneumatic sole for shoes comprising upper and lower spaced walls composed of an inner body or lining of canvas or similar fabric and a 95 thick outer rubber covering, and intervening side walls of rubber following the periphery of the first mentioned walls and the

contour of the foot, to constitute an air chamber jointly therewith, all of said walls and their component parts being vulcanized together to form a unitary one piece structure of sufficient weight and stiffness to hold its form when cemented or similarly secured with its upper wall against the sole of a shoe

and means for permitting the introduction of air under pressure within said chamber.

JOHN P. KENNY.
